ELECTRIC VAPORIZER

Max Katzman, Utica, N. Y., assignor to Kaz Manufacturing Company, Inc., Utica, N. Y., a corporation of New York

Application March 3, 1930, Serial No. 432,841

12 Claims. (Cl. 219—40)

This invention relates to an electric liquid-vaporizer in which a pair of electrodes are enclosed within and supported by an insulating block which in turn is mounted upon and suspended from the cover of the liquid container in such manner that the lower end thereof in which the electrodes are incorporated is immersed in the liquid and provided with passages above and below the electrodes to allow the circulation of the liquid therethrough and between said electrodes so that when the latter are energized the short circuit of the current across the intervening gap will rapidly convert the liquid into vapor until the level of the liquid drops below the electrodes at which time the circuit will be automatically broken.

This device is adapted to be used more particularly for medicinal purposes for vaporizing medicated liquids and discharging the vapor into the room in which the affected person is located to be inhaled by that person, but it is obvious that the same device may be used for vaporizing any other liquid.

The main object is to entirely enclose and conceal the electrodes within and upon an insulating block which in turn is secured to and supported by the cover of the container so that when the cover with the insulated electrodes thereon is removed from the container while the electrodes are still connected in the heater circuit the cover and insulator may be handled with perfect safety and without danger of contact of the electrodes with the hands or other external objects.

Another object is to provide the insulator with liquid passages at the lower and upper edges of the electrodes to permit free circulation of the water through the intervening gap between the electrodes to the exterior of the insulator and thereby to assure a rapid conversion of the liquid into vapor with a minimum consumption of current energy.

Another object is to make the insulator in half sections identical in construction so that both may be cast or molded in one and the same mold.

Another object is to make both of the electrodes and their supporting conductors identical in construction so that both may be made from one and the same pattern.

A further object is to construct the sections of the insulator and the electrode members in such manner that when the parts are assembled the electrodes will automatically be secured in properly spaced relation to form the intervening liquid gap.

Another object is to provide the upper ends of the half sections of the insulator with similar reduced extensions threaded externally for passage through an opening in the cover to be en-

gaged by a clamping nut which serves the double purpose of locking the two half sections together and also of locking both sections to the cover.

Other objects and uses relating to specific parts of the device will be brought out in the following description.

In the drawing:

Figure 1 is a perspective view of a liquid vaporizer embodying the various features of my invention.

Figure 2 is a vertical sectional view taken in the plane of line 2—2, of Figure 1.

Figure 3 is a vertical sectional view taken in the plane of line 3—3, Figure 2.

Figure 4 is a perspective view of one of the half sections of the insulator block.

Figure 5 is a perspective view of one of the electrodes and its electric conducting support.

As illustrated the liquid container comprises a relatively small jar 1, preferably of glass or other suitable insulating material, having a relatively large opening 2 in its upper end adapted to be normally closed by a cap or cover section 3 which, in this instance, is provided with a downwardly projecting marginal threaded flange 3' adapted for screw engagement with corresponding peripheral threads on the upper end of the container to permit the removal of the cover when desired.

This cover is preferably made of sheet metal or other suitable material and is provided with a central opening 4 for receiving the upper reduced end of the insulator block presently described, said cover being also provided with a delivery nozzle 5 having a vapor outlet 5' leading from the interior of the upper end of the container between the central opening 4 and marginal edge of the container as shown more clearly in Figure 2.

The electric heater for vaporizing the liquid in the container 1 comprises, in this instance, a pair of similar L-shaped electrodes or plates 6 enclosed within and supported by an insulator block 7 in such manner that the electrodes will be held in parallel vertical planes and in opposed spaced relation to form an intervening liquid gap 8 which communicates with the exterior of the insulator block through an underlying vertical passage 9 and overlying lateral passages 10, said passages being arranged in planes below and above the corresponding lower and upper edges of the electrode plate 6 as shown more clearly in Figures 2 and 3.

The electrode plates 6 are preferably made of sheet steel or other suitable electric-conducting material and are each provided near their outer edges with upwardly projecting offset extensions 6' which, when the electrodes are placed in operative position, will be arranged in reverse or

der or at opposite sides of the longitudinal center of the insulating block 7.

Separate conductors or strips 11 of sheet copper or other electric conducting material are riveted or otherwise rigidly secured at their lower ends to the upper ends of the corresponding extensions 6' of the electrodes 6 to extend upwardly therefrom, the upper end of each strip 11 being electrically and securely connected to the adjacent ends of suitable lead wires 12 which in turn are enclosed in insulating sheathings 13 and are connected to an electric plug 13', the latter being adapted to be attached to any available electric socket to which current is supplied from any available source of electric energy, not shown, for supplying current to the electrodes 6.

The combined lengths of each of the electrodes 6 with its extension 6' and leader strip 11 is appreciably less than the vertical height of the insulating block 7 and in like manner the transverse width of each electrode is appreciably less than the corresponding width of the insulating block, the object of which is to permit each electrode with its extension 6' and leader strip 11 to be incorporated entirely within the marginal edges of the insulating block in a manner presently described so that in case the cover 3 with the insulating block and electric heater therein should be removed from the container 1 none of the electrically energized parts could come in contact with the hands of the user or any other external objects, all of which gives reasonable assurance of safety from electric shocks or fires when the device is used by the most careless or unskilled operatives.

The material from which the electrodes are constructed is adapted to resist disintegration through electrolytic action for as long a period as possible but obviously they will need replacing when their efficiency is seriously impaired and in order that they may be properly assembled in the first instance and replaced from time to time the insulator block 7 is preferably composed of similar half sections 7' having substantially flat meeting faces abutting against each other when the electrodes 6 with the extensions 6' and leader strips 11 are properly assembled within the insulating block.

In other words the insulating block 7 as a unit is substantially rectangular and elongated vertically as well as transversely in one direction, the transverse width being substantially less than the diameter of the opening 2 in the mouth of the bottle to permit the insulator to readily pass therethrough, the vertical height of the insulator block being appreciably less than the vertical depth of the interior of the container 1 so as to leave a clear open space across the bottom and entirely around all sides of the insulator when the cap 3 with the insulator thereon is secured in operative position upon the mouth of the container.

It is now evident that when the level of the liquid within the container has been lowered by evaporation of the liquid below the lower edges of the electrodes 6 it will automatically open the heater circuit by reason of the fact that the liquid formerly acting as a conductor between the electrodes will then cease to act as such conductor and therefore any further evaporation of the previous liquid charge will also cease.

This automatic opening of the heater circuit by the recession of the liquid from the electrodes introduces another safety factor in the opera-

tion of the device and at the same time tends to conserve the medicated liquid used for the reason that any quantity within the capacity of the container may be used for vaporizing purposes so long as the amount of liquid is sufficient to cover even a small part of the electrodes.

I have found that electrode plates of relatively small area arranged in a definite relation to each other and to the circulating passages as 9 and 10 are highly important in the conservation of electric energy and rapidity of ebullition and resultant vaporization and one of the objects of the present invention is to construct the insulating sections and also the electrode members and their leader strips in such manner that each half insulator section constitutes a unit-supporting means for one of the electrodes and its conducting strip so that when the two half sections of the insulator are secured together face to face they will not only secure the electrodes in operative position against relative movement but will also hold them in the most efficient predetermined relation for conservation of energy and rapidity of evaporation.

To this end the inner adjacent sides of the insulator sections are provided with electrode chambers or recesses 14, each having an upwardly projecting offset extension branch 15, which, together with the recesses 14, is substantially L-shaped to conform more or less closely to the shape of the plate electrodes 6 and its extension 6', each half section 7' being also provided with a lengthwise groove or channel 16 leading from the upper end of the extension 15 to an upper offset recess or channel 17 which in turn communicates with the central lengthwise groove 18 in the upper end of the section 7' thus forming a continuous channel leading from the electrode chamber 14 to the cover 3 for the reception of the conductors 6', 11 and 12 of the electrodes 6.

Each electrode 6 is seated in its like chamber 14 between the passages 9 and 10 so that the extensions 6' will lie in the corresponding branch recesses 15 while the conducting strip 11 will be seated in the groove 16.

The depth of each recess 14 and its branch 15 is somewhat greater than the thickness of the corresponding electrode 6 and its extension 6' so that when the conducting strips 11 of each electrode are seated on the bottom of its groove 16 and the two insulator sections are brought together face to face both of the electrodes 6 will be disposed in spaced relation at opposite sides of meeting faces of insulator sections to form the liquid gap 8 shown more clearly in Figure 2.

Under these conditions the upper ends of the extensions 6' will be more or less closely engaged with the upper end walls as 16' of the recesses 15 while the lower edges of the electrodes 6 will be in more or less close engagement with the lower end walls of their respective recesses 14 as shown in Figures 2 and 3.

The lower passage 9 is centrally arranged in the bottom of the insulator block with approximately one-half of the opening in each of the sections 7', said passage being elongated in one direction or in a plane parallel with the electrodes to allow the liquid to readily pass therethrough into the liquid gap 8.

The lateral openings 10 are preferably circular and arranged in transverse alignment in a plane directly over the upper edges of the main body of the electrodes 6 so that as the liquid

between the electrodes is heated and expanded it may readily flow outwardly in opposite directions through the passages 10 and as converted into vapor the latter will readily collect in the upper part of the receptacle to be discharged through the nozzle 5 into the room in which the vaporizer is located.

The offset recesses 17 in the inner faces of the upper portions of the insulator sections 7' 10 are also arranged in reverse order to receive the adjacent ends of the insulated wires 12, said wires with their insulated sheathings being passed outwardly from the upper ends of the strips 11 through the central lengthwise grooves 15 or openings 18 for connection with the plug 13'.

When the electrodes 6 with their extensions 6' and strips 11 together with the adjacent ends of the cables 12 are assembled in their respective recesses within the sections 7' the latter are 20 brought together face to face and firmly clamped together by clamping bolts 19 which are passed through registering apertures in the sections 7' along the longitudinal centers thereof, the threaded ends of the bolts 19 being engaged by 25 nuts 19'.

It will be observed upon reference to Figure 4 that the recesses 14 extend across the longitudinal centers of the inner faces of the insulator sections 7' equal distances therefrom and 30 that the branch recesses 15 and their grooves 16 will be arranged equal distances from and at opposite sides of the longitudinal center of said insulator sections when the latter are secured together under which conditions the recesses 17 of the two sections will extend in opposite directions from the central openings 18 the latter being then registered with each other to receive the cables 12.

In order that the connections, preferably soldered, between the upper ends of the conducting strips 11 and adjacent ends of the conductors 12 may have ample clearance to allow the sections 7' to be brought together face to face, the adjacent portions of said sections are provided with circular recesses 20 into which said connections may be seated as the two insulator sections are clamped together.

It is now clear that when the connecting strips 11 are seated in their respective grooves 16 the outer face of each will be seated against the bottom of its groove while the inner face of the same strip will be more or less in close engagement with the inner flat face of the other insulator section, thereby assuring the maintenance of 55 the electrodes in fixed spaced relation against relative movement toward or from each other with the assurance that the liquid gap 8 will always be the same.

The upper ends of the half sections 7' are 60 reduced in width to form semi-cylindrical nipples 21 extending through the opening 4 in and beyond the upper face of the lid 3 and forming end shoulders 22 at opposite sides of the nipples to engage the lower face of the lid, said nipples 65 being threaded externally to receive a hollow clamping nut 23.

When the insulator sections with the electrodes therein are clamped together by the bolts 19 the threaded extensions 21 will be aligned 70 with each other to form a cylindrical externally threaded nipple which is passed through the central opening 4 in the cover 3 until the shoulders 22 of the insulator sections 7' abut against the inner face of said cover whereupon the tubular nut 23 will be screwed upon the threaded 75

nipple sections 21 until the inner end of the nut engages the outer face of the cover, thereby not only locking the upper ends of the insulator sections to each other but also locking the entire insulating block to the cover, said nut being provided with a central opening through which the cables 12 are extended for attachment to the plug 14.

83

Operation

85

When it is desired to use the device for vaporizing liquid the cover 3 with the entire heating unit including the insulator block 7 may be removed from within the container to allow the latter to be filled more or less to any predetermined level above the lower edges of the electrodes 6 whereupon the cover 3 with the insulator block 7 thereon, may be secured in operative position upon the top of the container after which the plug 13' may be attached to an electric socket for supplying current to the electrodes 6.

90

The liquid which is then present in the gap 8 between the electrodes will be heated by the transit of the current from one electrode to the other through the intervening liquid until said liquid is vaporized and the vapor allowed to pass out through the nozzle 5.

95

This vaporization may continue until the liquid level drops below the lower edges of the electrodes whereupon the liquid electric connection between the electrodes will be broken with the resultant automatic breaking of the heater circuit.

100

During this vaporization of the liquid within the container said liquid is free to flow upwardly through the passage 9 and thence through the gap 8 and outwardly through the passages 10 as long as the liquid level remains above the lower edges of the electrodes.

105

It will be observed that the water heating chamber or gap between the electrodes is closed and entirely confined within the walls of the insulator block except for the liquid inflow opening 9 at the bottom and the lateral vapor outlets 10 at the top of the water heating chamber, the object of which is to confine the ebullition as closely as possible to the water heating chamber between the electrodes and thereby to prevent ebullition in the upper portion of the container which is automatically reserved for the reception of the vapor escaping from the passages 10 into the adjacent portions of the receptacle for collection in the upper portion thereof and for final discharge through the 130 nozzle 5, thus preventing any possibility of escape of the liquid through the nozzle.

110

What I claim is:—

1. In an electric vaporizer of the character described, a container for the liquid to be vaporized having a removable cover and a vapor outlet therein, a pair of upright insulator sections secured to the cover and arranged in opposed abutting relation within the container and provided with similar electrode-receiving chambers 140 in adjacent sides near the lower ends thereof, and a pair of similar electrodes arranged in opposed spaced relation within said chambers to form an intervening liquid space in the plane of the abutting faces of said sections, each insulator section having an opening in the bottom wall of its recess below the corresponding electrode and registering with said space and also provided with an opening in the side wall of its chamber above the adjacent electrode 150

125

135

140

145

150

- and communicating with said space to allow circulation of the liquid from the lower opening upwardly through said space and outwardly through the side openings.
5. 2. An electric vaporizer as in claim 1 in which the upper ends of the insulator sections are provided with reduced threaded extensions and a nut engaging said extensions for clamping the sections together.
10. 3. An electric vaporizer as in claim 1 in which clamping bolts are passed through transverse openings in the insulator sections for clamping them together face to face.
15. 4. In an electric vaporizer of the character described, a container for the liquid to be vaporized, opposed separable insulator sections supported within the container in abutting relation and provided with an electrode chamber in the opposite sides of their abutting faces, and a 20 pair of electrodes arranged in opposed spaced relation within said chambers to form an intervening liquid space in the plane of the abutting faces, said chambers having openings to allow circulation of liquid from the bottom upwardly 25 between the electrodes.
30. 5. An electric vaporizer comprising in combination, a container for the liquid to be vaporized having a removable cover provided with a vapor outlet, a pair of separable insulator sections secured to the cover to extend therefrom into the container in opposed relation and having portions of adjacent sides abutting against each other and other portions of said adjacent sides provided with registering electrode-receiving 35 chambers near the lower ends of the sections, channels leading upwardly from the chambers in laterally offset relation, and electrodes seated in said chambers in spaced relation and provided with electric conductors seated 40 in their respective channels in spaced relation, said conductors being extended to the exterior of the container for connection to a source of electric supply.
45. 6. In an electric vaporizer, the combination with a container for the liquid to be vaporized having a removable cover provided with a vapor outlet, of a pair of opposed insulator sections secured to the cover to extend downwardly therefrom into the container and having adjacent sides in abutting relation and provided with registering electrode-receiving chambers near the lower ends thereof and channels leading upwardly from the chambers, opposed electrodes seated in said chambers and having adjacent sides disposed in spaced relation to allow the passage of the liquid between them, and means for securing the sections to each other.
50. 7. In an electric vaporizer, the combination with a container having a removable cover provided with a vapor outlet, of an insulator block extending downwardly from the cover into the container and divided medially from top to bottom to form separable sections abutting face to face, the adjacent sides of said sections being provided with laterally elongated registering chambers near their lower ends and with relatively narrow channels extending upwardly from their respective chambers to the top of the block, electrodes arranged in said chambers in 65 opposed spaced relation, and electric conductors connected to their respective electrodes and ex-
- tending along the corresponding channels to the exterior of the container for connection to a source of current supply.
8. An electric vaporizer as in claim 7 in which clamping bolts are passed through registering openings in both sections for holding the latter in abutting relation.
9. An electric vaporizer comprising a container having a removable cover, an insulator block abutting endwise against the underside of the cover and extending downwardly therefrom into said container and having its upper end provided with a reduced externally threaded nipple extended through an opening in the cover, a nut engaging said nipple and upper face of the cover for clamping the insulator block to said cover, and electrodes mounted on the insulator block and provided with means for connection to a source of current supply.
10. An electric vaporizer comprising a container having a removable cover, an insulator block abutting endwise against the underside of the cover and extended downwardly therefrom into said container and having its upper end provided with a reduced externally threaded nipple extended through an opening in the cover, said insulator block being divided medially from end to end through the nipple to form opposite half sections, a nut engaging the nipple for clamping the sections to each other and to the cover, and electrodes seated in recesses in the adjacent sides of the sections in spaced relation and provided with conductors extending through openings in the nipple and nut for connection with a source of current supply.
11. In an electric vaporizer, the combination with a container for the liquid to be vaporized having a removable cover provided with a vapor outlet, of a pair of opposed insulator sections supported from the cover and extending into the liquid in the container and having adjacent sides in abutting relation and provided with registering electrode-receiving chambers near the lower ends thereof and channels leading upwardly from the chambers, opposed electrodes seated in said chambers and having adjacent sides disposed in spaced relation to allow the passage of liquid between them, and means for securing the sections to each other.
12. In an electric vaporizer, the combination with a container for the liquid to be vaporized having a removable cover provided with a vapor outlet, of a unitary electrode and insulator structure suspended from the cover and extending into the liquid, said unitary structure comprising a pair of opposed insulator sections having adjacent sides in abutting relationship and chambers formed therein and channels extending upwardly from said chambers, a pair of electrodes mounted in said chambers, means for securing the insulator sections together whereby the electrodes are retained by the insulator sections in spaced relationship and against turning, said insulator sections being at least partly open between the electrodes to enable free circulation of the liquid to be vaporized therebetween, and a pair of conductors mounted in said channels and secured to the electrodes for conducting current thereto.

MAX KATZMAN. 145
